COMBINED FISH SCALER AND CLEANER

Clarence W. Velt Kamp, 4434 N. Pacific Highway,
Central Point, Oreg.

Filed July 7, 1964, Ser. No. 80,735

Term of patent 14 years

(Cl. D9—6)

FIGURE 1 is a plan view looking toward one side of the combined fish scaler and cleaner;

FIGURE 2 is a similar view looking toward the opposite side thereof;

FIGURE 3 is an edge elevational view of the combined fish scaler and cleaner looking from top to bottom of FIGURE 2;

FIGURE 4 is an edge elevational view looking in the opposite direction to FIGURE 3, and

FIGURE 5 is a cross sectional view taken substantially along a plane as indicated by the line 5—5 of FIGURE 4.

I claim:

The ornamental design for a combined fish scaler and cleaner, substantially as shown.
